CLAIM

The ornamental design for a garlic squeezer, as shown.

DESCRIPTION

FIG. 1 is a side elevational view of a garlic squeezer showing my new design;

FIG. 2 is a front elevational view thereof;

FIG. 3 is a cross-sectional view taken through lines 3—3 of FIG. 1;

FIG. 4 is a bottom plan view thereof;

FIG. 5 is a top plan view thereof;

FIG. 6 is a perspective view thereof.

FIG. 1.FIG. 2.FIG. 3.FIG. 4.FIG. 5.FIG. 6.
